ATTORNEYS

UNITED STATES PATENT OFFICE.

MARGARET HAYES, OF BROOKLYN, NEW YORK.

WINDOW-CLEANING DEVICE.

Application filed July 20, 1926. Serial No. 123,713.

This invention relates to window cleaning devices.

Some of the objects of the present invention are: to provide a cleaning device especially adapted for cleaning outside surfaces of windowpanes quickly and conveniently; and to provide a device of the indicated character which is extremely simple in construction and comparatively inexpensive.

With the foregoing, other objects of the invention will appear from the embodiment of the invention which by way of example is described in the following specification and illustrated in the accompanying drawings, in which—

Figure 1 is a perspective view of the device embodying the features of the present invention.

Fig. 2 is a view illustrating the manner in which the device of the present invention is used.

Fig. 3 is a rear elevation of the cleaning element attached to the supporting member of the manipulator of the device.

Fig. 4 is a sectional view taken on the line 4—4 of Fig. 3.

The device of the present invention is intended to be used by a person for cleaning the outside surfaces of windowpanes from the inside. The device generally stated comprises a manipulator 10 and one or more cleaning devices 11 capable of being detachably associated with the manipulator for carrying out different cleaning operations.

The manipulator 10, in the present instance, is in the form of a frame substantially of U-shape to provide what may aptly be termed an outside section 12 and an inside section 13. The outside section 12, and a part of the inside section 13 are produced from a single piece of stout wire which is bent upon itself to provide a supporting member or cross-piece 14 included in the outside section 12 and members 15 which extend into a suitable handle 16 which are included in the inside section 13. The sections 12 and 13 are connected by portions 17 upon which the device may be suspended when desired.

As before stated two or more cleaning devices 11 may be provided which will be substantially similar in construction except for the cleaning surfaces used, which may be felt, brush bristles, or analogous means.

The cleaning element 11 is representative of one type, and includes a block 18 to which is

secured a felt cleaning pad 19. Means is provided on the block 18 which coacts with the cross-piece 14 of the manipulator 10 for detachably retaining the cleaning element 11 on one end of the manipulator 10. In the present instance said means consists of spaced parallel portions 20 provided by virtue of the provision of a groove 21 in the back face of the block 18, and a retaining member in the form of a plate 22 connected to the block 18 by a screw or the like 23 to permit the member 22 to be moved to lie over the groove as shown in Figs. 3 and 4 or to be moved to the dotted line position shown in Fig. 3 to one side of the groove 21. When the member 22 is in the position to one side of the groove 21, the cross-piece 14 may be disposed in said groove, whereupon, the member 22 is brought to a position to lie over the groove 21. In the latter position a portion of the member 22 will coact with the portions 20 and thus releasably or detachably hold the cleaning element 11 on one end of the manipulator 10. It is also to be noted that the cleaning element 18 will be permitted to have relative pivotal movement with respect to the manipulator.

In use, with the cleaning element 11 attached, it is only necessary to lower the upper window sash for instance, and then bring the manipulator over the same as shown in Fig. 2 and in the hand of a person the handle 16 may be manipulated to cause the cleaning element to be reciprocated properly over the entire outer surface of the windowpane, and in that way be thoroughly and effectively cleaned. One type of cleaning element may be used for carrying out a washing operation, and a second type of cleaning element may be used for drying the washed surface. When desired the device may be used for cleaning the outside surface of a windowpane of a lower window sash by simply raising the lower sash and bringing the device in place from beneath the lower rail of the window sash.

The portions or sections 17 are very important as they permit an easy operation in cleaning the exterior surfaces of both the upper and lower sashes. These sections may be of any length and are always sufficient to permit the pad 19 to be readily brought into engagement with any part of the exterior surface of either sash by extending the part over the sash or under the sash as circumstances may direct.

I claim:

1. A window cleaning device comprising a substantially U-shaped frame having a handle at one end, and a cross-piece at the opposite end; a cleaning element including a block, said block having a groove therein providing spaced parallel portions between which said cross-piece is adapted to be disposed, a retaining member, and means connecting the retaining member to the block for movement over said groove to detachably retain the cross-piece therein.

2. A window cleaning device comprising the combination of a frame having a handle for manipulating the frame, and a cleaning element including a block having a groove therein providing spaced portions between which a portion of said frame is adapted to be disposed, a retaining member, and means connecting the retaining member

with the block for movement, said retaining member being movable over said groove to detachably connect the cleaning element with the frame.

3. A window cleaning device comprising the combination of a frame and a cleaning element, said frame having a handle at one end for manipulating the frame, said frame having a cross-piece at the end remote from the end having the handle, said cleaning element including a block having a groove therein adapted to receive said cross-piece, a retaining member, and means connecting the retaining member with the block for movement, said retaining member being movable over said groove to retain said cross-piece in the groove and thus effect a pivotal connection of the cleaning element with the frame.

MARGARET HAYES.
